Primary Examiner — Karen E Kearney*Assistant Examiner* — John Reickel(74) *Attorney, Agent, or Firm* — Maginot, Moore & Beck LLP**CLAIM**

The ornamental design for a display screen with graphical user interface, as shown and described.

DESCRIPTION

The single FIGURE is a front view of a display screen with graphical user interface showing my new design.

The broken line showing of the display screen is for environmental purposes only and forms no part of the claimed design.

1 Claim, 1 Drawing Sheet
